UNITED STATES PATENT OFFICE

MARTIN C. BERSTED, OF SAN DIEGO, CALIFORNIA

SELF-ALIGNING TERMINAL SOCKET

Application filed December 7, 1925. Serial No. 73,622.

My invention relates to self-aligning terminal sockets for use in connection with electric connection plugs for making an electrical connection with flatirons or other heating apparatus.

The objects of my present invention are: first, to provide a terminal socket of this class which is adapted to receive and clamp round and flat, as well as other terminals of different cross-sections; second, to provide a terminal socket having oppositely disposed members for receiving and clamping a terminal post therebetween, said members being variously separable and adapted to assume various positions relatively to each other, thereby permitting said members to readily and securely clamp terminals of various sizes, shapes and inclinations; third, to provide means of this class having a yieldable U-shaped support, at the ends of the arms of which is pivotally mounted, intermediate their ends, a pair of oppositely disposed terminal contacting members adapted to assume various angular positions relatively to each other as well as various separated parallel positions; fourth, to provide a very compact and efficient terminal socket particularly adapting the same for connection plug construction for electric flatirons; fifth, to provide as a whole a novelly constructed self-aligning terminal socket, and sixth, to provide a device of this class which is simple and economical of construction, durable, and which will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had to the accompanying drawings and to the characters of reference thereon, which form a part of this application, in which:

Figure 1 is a side view of a special electric connection plug adapted to be used for connecting the electric circuit to flatirons, showing the loose side member removed to facilitate the illustration of the terminal

sockets mounted therein; Fig. 2 is an enlarged side view of one of the terminal sockets; Fig. 3 is an edge view thereof, showing by dotted lines one of the supporting arms and the contact forming member connected therewith separated from the other contact forming member in a manner to receive a terminal post; Fig. 4 is a similar view thereof, showing the contact forming members separated in parallel relation and showing by dotted lines a terminal post positioned therein; Fig. 5 is an end view thereof, taken at 5-5 of Fig. 4; Fig. 6 is a transverse sectional view thereof, taken through 6-6 of Fig. 4, and Fig. 7 is a fragmentary sectional view thereof, taken through 7-7 of Fig. 2.

Like characters of reference refer to similar parts and portions throughout the several views of the drawings.

Referring to the drawings, Fig. 1 shows the supporting means for the terminal sockets as an electric connection plug casing 1 of a special type and adapted to be used for connecting the electric current to a flatiron or the like. The casing 1 is provided with a removable member extending over a portion only of one side of the casing and fitting in a correspondingly shaped recess 1a, as shown in Fig. 1. With the special construction of terminal sockets, as will be described hereafter, the casing 1 is made particularly short, particularly adapting the same for electric flatirons. The electric cables supplying electrical energy to the terminal sockets enter the casing through an extended sleeve portion 1b extending to one side and partially backwardly from the main portion of the casing so as to reduce interference of the cable with the operator of the heating apparatus to a minimum.

The means for supporting the contact forming members or terminal contacting members or terminal socket members, in particular relations with each other, is substantially U-shaped and consists of a pair of oppositely disposed supporting members 2 and 3, which are secured together at their coincident rear ends and free or separated at their forward ends. The normally forward portions of the supporting members 2 and 3

are offset toward each other and are provided in said offset portions with longitudinally extending grooves or channels 2a and 3a. The supporting member 2 extends straight backwardly and is provided at its normally rear end with a flat circular recess 2b in which is positioned the normally rear end of the supporting member 3, which member 3 extends at a right angle to the member 2 and is provided with a looped spring portion 3b connecting its right angle bent portion with its straight, normally forward portion. In the rear recess 2b of the member 2 is also positioned the rear end 4a of an auxiliary spring member 4, which is positioned outside of and conforms substantially with the contour of the supporting member 3 and is adapted to supplement the spring action of the member 3 at its bulged portion. The rear ends of the supporting members 2 and 3 and of the spring member 4 are secured together by folding inwardly the portions 2c of the member 2, forming the side wall of the recess of said member, as shown best in Fig. 2.

25 The terminal contacting members or socket members 5 and 6 are formed of sheet metal plates with longitudinal grooves or channels 5a and 6a at their adjacent sides, said channels forming corresponding ridges at their outer sides, which are positioned in the corresponding channels 2a and 3a of the supporting members, as shown best in Fig. 6. The portions of the supporting members 2 and 3 at either side of the grooves or channels 2a and 3a therein, as indicated by 2d and 3d in Fig. 6, are flat and form flat bearing surfaces for corresponding flat portions 5b and 6b of the terminal socket members 5 and 6, respectively. The flat portions 5b and 6b of the terminal socket members provide extended engaging surfaces for receiving and holding flat terminal posts, while the oppositely disposed channels 5a and 6a thereof provide an extended socket therebetween for holding round or polygonally shaped terminal posts. The normally forward ends of said socket members 5 and 6 are turned outwardly, as indicated by 5c and 6c, to facilitate the introduction of terminal posts, either flat, round or polygonal, into the sockets formed by said members 5 and 6.

Near the free or forward ends of the supporting members 2 and 3 are provided recesses or slots 2e and 3e through which extend, respectively, outwardly directed lugs 5d and 6d positioned intermediate the ends of the socket members 5 and 6. These lugs 5d and 6d are also bent forwardly to prevent ready removal of the socket members from their respective supporting members.

With this type of construction of terminal socket, a terminal post may be inserted between the members 5 and 6 separating them, as shown by dotted lines in Fig. 3, against the

spring action of the supporting member 3 and the spring member 4. Further insertion of the terminal post permits the socket members to engage over a long surface of the opposite sides of the terminal post, whether parallel or tapered inwardly or outwardly and securely holds the same therebetween.

Through the normally rear ends of the members 2, 3 and 4 is provided a hole in which is screwably mounted the binder post screw 7 for securing the wires 8 of the cable 9 to the terminal sockets. The walls forming the recess 2b at the rear end of the supporting member 2 are extended at the portions not folded downwardly to secure the members 2, 3 and 4 together, forming yieldable lugs 2f for retaining the wire 8 around and underneath the head of the screw 7.

Though I have shown and described a particular construction, combination and arrangement of parts and portions, I do not wish to be limited to this particular construction, combination and arrangement, but desire to include in the scope of my invention, the construction, combination and arrangement substantially as set forth in the appended claims.

Having thus described my invention, what I claim as new and desire to secure by Letters Patent is:

1. In a device of the class described, a substantially U-shaped supporting means formed of a pair of oppositely disposed supporting members having free end portions and secured together at their other end portions, one of said members having an integral spring portion intermediate its ends, a pair of oppositely disposed terminal socket members, one pivotally connected intermediate its ends to the free ends of each of said supporting members in self-aligning relation therewith, said terminal socket members having longitudinal grooves at their adjacent sides providing terminal socket members for receiving and clamping terminals of various cross-sections, and an auxiliary spring member secured at the secured ends of said supporting members and extending around the spring portion of the one supporting member, the latter ends of the supporting members forming a binding post for an electric conductor.

2. In a device of the class described, a substantially U-shaped supporting means formed of a pair of oppositely disposed supporting members having free end portions and secured together at their other end portions, one of said members having an integral spring portion intermediate its ends, the free-end portions of both members being rectilinear and provided at the adjacent sides with longitudinal grooves, and a pair of oppositely disposed terminal socket members formed of thin metal with longitudinal grooves at their adjacent inner sides and correspond-

ing ridges at their outer sides, said ridges fitting the grooves of said supporting members forming means for aligning said terminal socket members with said supporting members, each of said terminal socket members being pivotally connected intermediate its ends to the free end of one supporting member, said terminal socket members being formed for receiving and clamping terminals of various cross-sections.

3. In a device of the class described, a substantially U-shaped supporting means formed of a pair of oppositely disposed supporting members having free end portions and secured together at their other end portions, one of said members having an integral spring portion intermediate its ends, the free-end portions of both members being rectilinear and provided at the adjacent sides with longitudinal grooves and near their extreme ends with recesses, and a pair of oppositely disposed terminal socket members formed of thin metal with longitudinal grooves at their adjacent inner sides and corresponding ridges at their outer sides, said ridges fitting the grooves of said supporting members forming means for aligning said terminal socket members with said supporting members, each of said terminal socket members being provided intermediate its ends with an outwardly directed pivotal retaining lug, the lugs of the terminal socket members being adapted to extend into the recesses of said supporting members for pivotally connecting said terminal socket members with the supporting members, said terminal socket members being formed for receiving and clamping terminals of various cross-sections.

4. In a device of the class described, a substantially U-shaped supporting means forming a pair of oppositely disposed, resilient supporting members having straight, free-end portions, each supporting member having an aperture adjacent its outer end, a pair of relatively long, straight terminal socket members having centrally positioned rearwardly extending lugs adapted to be received by said apertures and to pivotally support said socket members on said supporting members, said free-end portions forming bearing surfaces for said sockets over their central portion.

5. In a device of the class described, a substantially U-shaped supporting means forming a pair of oppositely disposed, resilient supporting members having straight, free-end portions, said free-end portions having lengthwise extending grooves, an aperture adjacent the outer end of each supporting member, a pair of relatively long, straight terminal socket members, having lengthwise extending ridges at their outer sides adapted to fit in said grooves and align said sockets relative to said supporting members, centrally positioned lugs extending from the outer sides of said socket members adapted

to be received by said apertures and pivotally support said socket members on said supporting members, said free-end portions forming bearing and aligning surfaces for said sockets over their central portion.

6. In a device of the class described, a substantially U-shaped supporting means forming a pair of oppositely disposed resilient supporting members having straight free-end portions and forming spaced apart bearing surfaces having lengthwise extending central channel portions and flat side portions, an aperture adjacent the outer end of each supporting member, a pair of relatively long, straight socket members having a lengthwise extending central ridge on their outer side and straight side portions adapted to be received and aligned by said bearing surfaces, centrally positioned lugs extending from the outer side of said sockets projecting through said apertures, the projecting portions of said lugs being bent toward the outer end of said socket members.

In testimony whereof, I have hereunto set my hand at San Diego, California, this 25th day of November, 1925.

MARTIN C. BERSTED.
